(57) **CLAIM**

The ornamental design for a freestand closet, as shown and described.

DESCRIPTION

FIG. 1 is a front, top perspective view of a freestand closet showing our new design;

FIG. 2 is a rear, bottom perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

Broken lines show articles that can be used with the claimed design, are provided for illustrative purposes only, and form no part of the claimed design.

1 Claim, 7 Drawing Sheets
